CLAMP FOR HOSIERY DRYING FORMS

Harry F. Wanamaker, Philadelphia, Pa., assignor
to Procter & Schwartz, Incorporated, Phila-
delphia, Pa., a corporation of Pennsylvania

Application May 12, 1937, Serial No. 142,309

3 Claims. (Cl. 223—75)

This invention relates to hosiery clamps for use with the stocking forms employed in hosiery drying machinery of all kinds and particularly that type of machine disclosed in the prior United States Letters Patent No. 1,126,619, dated January 26, 1915 and which issued to Walter M. Schwartz and Harry Coulston.

The present clamp constitutes an improvement on the clamp disclosed in the prior U. S. patent to Harry Coulston No. 1,190,119, dated July 4, 1916.

The object of the present invention is to simplify the clamp structure and to provide a clamp which prior to clamping the stocking firmly to the form on which it is stretched will grip the stocking at each side of the form and pull the welt of the stocking down on the form and remove any wrinkles that may be in the stocking, prior to drying.

In the accompanying drawings:

Fig. 1 is a side elevation showing a plurality of forms progressing through the boarding operation in a machine of the type noted;

Fig. 2 is a sectional elevation taken on the line 2—2, Fig. 1;

Fig. 3 is a sectional elevation taken on the line 3—3, Fig. 1;

Fig. 4 is a sectional elevation taken on the line 4—4, Fig. 1;

Fig. 5 is a sectional elevation taken on the line 5—5, Fig. 1;

Fig. 6 is an enlarged side elevation of one of the clamps shown in Fig. 1;

Fig. 7 is an edge elevation, partly in section, of the clamp shown in Fig. 6; and

Fig. 8 is a sectional plan view taken on the line 8—8, Fig. 7.

As disclosed in the above noted patents each of the stocking forms A is mounted in a carrier which is advanced along a predetermined path in a course partly within and partly outside a suitable drying chamber.

In that portion of the travel lying outside the drying chamber dried stockings are removed from the forms emerging from the drying chamber and damp stockings are placed on the forms prior to the entrance of the forms into the drying chamber.

Each form A is removably secured in a head 1 of a spindle 2 which latter is adapted to be mounted in a carriage (not shown) operating on a track in the drying machine.

In the present instance, the head 1 is provided with a central stem portion 3 having a slot 4 adapted to receive the lower end of the

stocking form A, with laterally extending ears 5, 5 projecting from opposite edges respectively of the stem 3 to clamp the form therebetween by means of clamp screws 6.

At each side of and spaced laterally from the stem 3 are guide standards 7, 7, providing recesses 8, 8 between the stem 3 and said standards at each side of the head 1 for reception of clamp members 10, 10 respectively.

Each clamp member 10 is of flat planar form 10 and preferably comprises a piece of fine wire mesh screen 11, composed of non-corrosive wire, stretched over a gridded framework 12 which includes a central horizontal bar 13 and laterally spaced vertical bars 14, 14 intersecting the central bar 13 and a marginal member 15 around which the wire screen is stretched and secured in place by corner pieces 16, 16. The wire mesh screen has edge bars 17, 17 lying parallel to the marginal elements 15 of the clamp grid frame, which are held in place by said corner elements 16.

The central bar 13 is provided with a pair of studs 18, 18 which project from and are perpendicular to the plane of the grid frame. The outer ends of the studs 18 pass through and are loosely mounted in the opposite ends respectively of a cross bar 19 of a T-shaped carrier for each clamp member 10.

A spring 20 encircles each stud 18, between the clamp frame and the cross bar 19 and exerts pressure therebetween which holds the clamps 10, 10 substantially parallel to each other and to the form A located between the clamp elements 10, 10.

Collars 21, 21 on the outer ends of the studs 18, 18 prevent the studs from pulling out of the cross bar 19.

The T-shaped supporting members include vertical shanks 22 which are slidably mounted in the standards 7, 7 respectively. Each shank 22 is provided with two pairs of laterally extending 40 projections or pins 23, 23 and 24, 24. The pair of pins 24, 24 are located adjacent the lower or free end of the shank 22, while the pins 23, 23 are located along said shank intermediate the pins 24 and the cross bar 19.

The pins 23, 23 and 24, 24 are adapted to slide in vertical grooves or guideways 25, 25 formed in oppositely disposed relatively spaced portions 26, 26 of each standard 7 and which provides a channel 27 between said portions in which the shanks 22 are located.

At the upper and lower ends respectively of the guideways 25, 25 are provided with stop abutments 28, 28 and 29, 29 which limit the movement of the shank 22 in the space 27 by the upper 55

pins 23 on the shank engaging the top abutments 28 and the lower pins 24 engaging the lower abutments 29.

The lower end of each shank 22 is provided with a stud 30 on which is rotatably mounted a roller 31. The rollers 31, 31 are adapted to engage and ride against rails 32, 32 and 33, 33 which are retained in fixed position along the path traveled by the forms A.

10 The guideways 25, 25 are provided with intersecting passages 34, 34 through which the lower pins 24, 24 are adapted to pass while the pins 23, 23 are retained within the guideways 25, 25 and function as fulcrums for the shanks 22, 22 whereby the lower ends of the shanks swing outwardly and the cross bars and the clamp members 10, 10 carried thereby swing inwardly to bring the clamp members 10, 10 flatly against the opposite faces of the form A into contact with the welt of the stocking mounted on said form.

15 As shown in Figs. 1 and 2, the clamps 10, 10 normally lie in a low position within the recesses 8, 8 while a dry stocking is being removed from the form A and a wet stocking B is being placed thereon.

The boarder pulls the welt C down on the board or form A into approximately the first position shown at the left hand side of Fig. 1.

20 The rollers 31, 31, as the form A moves along toward the right, first engage the inclined rails 32, 32 which raises the T-shaped supports of the clamps 10 until the form reaches the third position in Fig. 1, at which the pins 23, 23 on the shank 22 are in engagement with the upper abutments 28, 28 on the standards 7, 7 and the pins 24, 24 are in line with the cutouts 34, 34 in the guideways 25, 25.

25 The rollers 31, 31 then engage ribs 35, 35 on the rails 32, 32 and the rails flare outwardly. As the form continues to move the flaring of the rails, from the position shown in Fig. 3 to the position shown in Fig. 4, causes the shanks 22, 22 to swing outwardly at their lower ends, causing the clamps 10, 10 to engage the stocking welt C flatly on each of the opposite faces of the form A.

30 The rollers 31, 31 then move under the rails 33, 33, as shown in Figs. 1 and 5, which moves the shanks 22 and the clamps 10, 10 downwardly, the clamps still being held firmly in contact with the stocking welt C by ribs 36, 36 on the lower sides of the rails 33. The downward movement of the clamps 10, 10 pulls the welt C of the stocking downwardly which removes wrinkles from the leg portion of the stocking and "sets" the stocking on the form.

35 In the course of travel of each form through and out of the drying chamber the clamps 10, 10 may be held continuously in contact with the welt C in which case the moisture evaporating from the welt passes through the wire mesh pad 11 and grid frame which supports said pad, or the clamps 10, 10 may be released immediately after "setting" of the welt C on the form A.

40 In either case the rollers 31, 31, to release the clamps, engage another inclined rail, similar to the rails 32, which raises the shanks 22 and converge to move the pins 24 back through the cutouts 34 into the guideways 25, whereupon the rails decline and lower the clamps 10, 10 into the recesses 8, 8 for a repeat of the operation.

45 Preferably, the clamps 10 are locked in contact with the stocking on the form A after the "setting" operation and during the whole of the

drying operation. This locking is accomplished by the guide pins 24, 24 being moved downwardly beyond the lower edges of the cutouts 34, 34 during the pulling down of the stocking by the rails 33. The rollers 31 ride off the rails 5 33, at the ends thereof, and the springs 20 rock the carriers of the clamps 10 slightly in the direction opposite to that in which the shanks 22 were previously rocked by the flaring of the rails 32, until the guide pins 24 come to rest against 10 the outer surfaces 37 of the standards which intersect the lateral passageways formed by the cutouts 34 and which function as locking shoulders for the pins 24, 24.

15 The clamps 10, 10 are prevented from moving downwardly to an excessive extent by the lower edges of the clamps 10 coming to rest on the upper edges of the stem 3 and ears 5.

20 The construction disclosed above and in the accompanying drawings provides for movement of the clamps 10, 10 to positions below the lower edges of the forms A, out of the way of the stocking boarders when placing stockings on the forms, while still keeping the clamps within the shortest possible radius with respect to the axis 25 of the spindles 2 about which the forms A and their complementary clamps, etc. revolve in their passage along their circuit of travel in the drying machine, which makes it possible to reduce the clearances for the forms at points in the 30 circuit where the forms may be required to turn while the clamps are in inoperative positions with respect to the form. This permits the forms to be run closer together in the machine which increases the capacity of the machine without 35 increasing the size of the machine.

I claim:

1. The combination of a hosiery form, a stocking clamp at one side of said form, a carrier for said clamp, a guideway for said carrier disposed in a plane substantially parallel to and spaced laterally from said side of said form and affording movement of said clamp longitudinally of the form in laterally spaced relation to said form, and a pivot for said carrier slidably mounted in said guideway and affording movement of said clamp from said plane into contact with said side of said form.

2. The combination of hosiery form, a stocking clamp at one side of said form, a carrier for said clamp, a guideway for said carrier disposed in a plane substantially parallel to and spaced laterally from said side of said form and affording movement of said clamp longitudinally of the form in laterally spaced relation to said form, a pivot for said carrier slidably mounted in said guideway, a guide for said carrier slidably mounted in said guideway in spaced relation to said pivot to maintain parallel movement of the clamp relative to the form, and a lateral passageway for said guide intersecting the path of movement thereof along said guideway for affording lateral movement of said guide and resultant pivotal movement of said carrier about the axis of said pivot retained in said 55 guideway for effecting movement of said clamp into contact with said stocking on said form.

3. The combination of a hosiery form, a stocking clamp at one side of said form, a carrier for said clamp, a guideway for said carrier disposed in a plane substantially parallel to and spaced laterally from said side of said form and affording movement of said clamp longitudinally of the form in laterally spaced relation to said form, a pivot for said carrier slidably mounted 70 in said guideway for effecting movement of said clamp on said form.

4. The combination of a hosiery form, a stocking clamp at one side of said form, a carrier for said clamp, a guideway for said carrier disposed in a plane substantially parallel to and spaced laterally from said side of said form and affording movement of said clamp longitudinally of the form in laterally spaced relation to said form, a pivot for said carrier slidably mounted 75

in said guideway, a guide for said carrier slidably mounted in said guideway in spaced relation to said pivot to maintain parallel movement of the clamp relative to the form, a lateral passageway for said guide intersecting the path of movement thereof along said guideway for affording lateral movement of said guide and resultant pivotal movement of said carrier about

the axis of said pivot retained in said guideway for effecting movement of said clamp into contact with said stocking on said form, and a shoulder spaced outwardly from said guideway along said lateral passageway for engagement by said guide to effect locking of the clamp in contact with the form.
